PNEUMATIC TUBE CARRIER

Maurice P. Anderson, Chicago, Ill.

Application August 2, 1940, Serial No. 349,694

6 Claims. (Cl. 243—35)

This invention relates to improvements in pneumatic tube carriers and has for its object to provide a new and improved device of this description.

The invention has as a further object to provide a pneumatic tube carrier having an indicating device at one end and a new and improved door or cover at the other end which may be opened to insert material in and remove it from the carrier. The invention has as a further object to provide a pneumatic tube carrier having a felt door or cover at one end, arranged to reduce the resistance of the passage of the carrier through the tube. The invention has as a further object to provide a pneumatic tube carrier having a door or cover at one end with a new and improved anchor strap and hinge. The invention has as a further object to provide a pneumatic tube carrier with a door or cover at one end and means for strengthening the door end of the carrier. The invention has as a further object to provide a pneumatic tube carrier with means for accurately holding the door or cover in position against the carrier when the carrier is moving through the tube and for preventing deformation of the door or cover.

The invention has further objects which are more particularly pointed out in the accompanying description.

Referring now to the drawing wherein I have shown one form of device embodying the invention,

Fig. 1 is a side view of the device;

Fig. 2 is an enlarged sectional view taken on line 2—2 of Fig. 1;

Fig. 3 is an end view looking at the cover or door end of the carrier; and

Fig. 4 is a view similar to Fig. 3, showing the door or cover opened.

Like numerals refer to like parts throughout the several figures.

The carrier illustrated in the drawing comprises a hollow receptacle 1 of any suitable material, having at one end an indicating device 2 of any suitable form or construction.

At the other end of the hollow receptacle 1 is a door comprising a member 3 of some suitable material, such, for example, as felt. The felt member has on opposite sides of it the discs 4 and 5 of rigid material, see Fig. 2. These discs are fastened together and fastened to the felt member 3, as by means of the fastening devices or rivets 6 and 7. The wall 8 of the hollow receptacle is provided with a reinforcing metal member which is preferably of U-shaped cross

section and which has the inner member 9 and the outer member 10, the members being integral and being looped over the edge of the wall 8. There is a metal ring 11 within the U-shaped reinforcing device and between the members 9 and 10 thereof. This construction strengthens and reinforces the end of the hollow receptacle against the blows which the carrier receives in use.

10 The cover or door is hinged in position by a flexible hinge. This flexible hinge as herein shown consists of a strap which passes around the metal ring 11 so as to provide a double hinge consisting of the members 12 and 13. The reinforcing device is cut away at the point where the hinge passes around the ring 11. This hinge is fastened to the felt member 3 by means of the fastening devices or rivets 14. There is a fastening device for fastening the door or cover in its closed position. As herein shown, this consists of a flexible member which is looped around the ring 11 and which therefore has two flexible sections 15 and 16. The felt member 3 is cut away at 17 to provide a notch for the fastening device. Attached to the felt member and associated parts is a locking member 18 which may be of any suitable form, and as herein shown, it has an enlarged end or head 19 and a reduced portion 20 near the outer end of the head. This locking member passes through the discs 4 and 5 and the felt member 3 and also preferably through the members 12 and 13 of the hinge device, and is preferably provided with an enlargement 21 for holding it in position. There 20 is also preferably a metal washer 22 between the head 19 and the hinge members 12 and 13. The fastening device is provided with a locking member 23 which is attached to the fastening device and which has an opening 24 into which the enlarged end or head of the locking member 18 is received.

40 There is a spring member in the locking member 23 which has two opposed members 25 and 26. When this locking member 23 is pressed down over the head 19 of the locking member 18 the spring members 25 and 26 spread out and then move into the reduced portion 20, thus holding the parts in position. When it is desired to release the locking member 23, it is simply pulled out and the springs move out around the enlargement at the end so as to release the two locking members. When a small pneumatic tube carrier is used only one locking device will be used. When a large pneumatic tube carrier is used I prefer to provide two locking devices. The

second locking device is similar to the first locking device and I have applied the same reference numerals with the exponent *a* attached thereto.

The locking member *18a* is provided with a spacer washer *27* so as to bring the locking member *23a* up to a position substantially level with the locking member *23* when the two locking members are in their locking position. This spacer washer also serves as a fender to resist impacts to the locks or fasteners when the carrier collides with obstructions.

There is a flexible piece or skirt *28* which extends around the end of the outer wall *8* and which preferably abuts against the member *3* of the door. This member *3* which is preferably made of felt, has a beveled edge *29* at the front. This beveled edge on the front of the door member *3* is very important as it assists the felt cover in passing through the tubes. This beveled edge allows the carrier and the felt cover to pass through or over terminal doors, terminal triggers, curves, offsets, unbotted and rough joints in the tube system without catching or momentarily holding the carrier during its transmission.

I claim:

1. A pneumatic tube carrier comprising a hollow receptacle having an outer wall, a U-shaped metal member looped over the edge of the wall at one end of said hollow receptacle, a metal ring enclosed in said U-shaped metal member, a door for closing said end, and a flexible hinge connected with said metal ring and said door.

2. A pneumatic tube carrier comprising a hollow receptacle having an outer wall, a U-shaped metal member looped over the edge of the wall at one end of said hollow receptacle, a metal ring enclosed in said U-shaped metal member, a door for closing said end, a flexible hinge connected with said metal ring and said door, and a fastening device for fastening said door in its closed position, comprising a flexible fastening member connected with said metal ring and removably connected with said door.

3. A pneumatic tube carrier comprising a hollow receptacle having an outer wall, a U-shaped metal member looped over the edge of the wall at one end of said hollow receptacle, a metal ring enclosed in said U-shaped metal member, a door for closing said end, a flexible hinge connected with said metal ring and said door, a fastening device for fastening said door in its closed posi-

tion, comprising a flexible fastening member connected with said metal ring and removably connected with said door, a locking member connected with said flexible fastening member, and a fixed locking member on the door to which said first mentioned locking member is removably connected.

4. A pneumatic tube carrier comprising a hollow receptacle having an outer wall, a U-shaped metal member looped over the edge of the wall at one end of said hollow receptacle, a metal ring enclosed in said U-shaped metal member, a door for closing said end, a strap hinged member comprising two lapping sections with a loop at one end in which said metal ring is received and fastening means for fastening the other end of said hinge to said door.

5. A pneumatic tube carrier comprising a hollow receptacle having an outer wall, a U-shaped metal member looped over the edge of the wall at one end of said hollow receptacle, a metal ring enclosed in said U-shaped metal member, a door for closing said end, a flexible hinge connected with said metal ring and said door, a fastening device for fastening said door in its closed position, comprising a strap comprising two lapping sections forming a loop at one end into which said metal ring is received, a fastening device connected with said strap, a fixed fastening device connected with said door and connecting devices on said fastening devices which removably connect the fastening devices together.

6. A pneumatic tube carrier comprising a hollow receptacle having an outer wall, a U-shaped metal member looped over the edge of the wall at one end of said hollow receptacle, a metal ring enclosed in said U-shaped metal member, a door for closing said end, a flexible hinge connected with said metal ring and said door, a fastening device for fastening said door in its closed position, comprising a flexible fastening member connected with said metal ring, two separated fastening devices connected with said door and extending along a diameter of the door, two fastening devices connected with said flexible fastening member and connecting devices for removably connecting the two fastening devices on the flexible member with the fastening devices on the door.

MAURICE P. ANDERSON.
